UNITED STATES PATENT OFFICE.

EDWARD O. C. ORD, OF THE UNITED STATES ARMY.

APPLICATION OF GUNPOWDER TO FLAT PROJECTILES, GIVING THEM ROTATION.

Specification forming part of Letters Patent No. 27,447, dated February 14, 1860.

To all whom it may concern:

Be it known that I, E. O. C. ORD, of the United States Army, have invented a new description of Fire-Arms and Projectiles; and I do hereby declare that, as nearly as may be, the following is an accurate description thereof, reference being had to the accompanying drawings and the letters of reference marked thereon.

The nature of my invention consists in giving, by an explosive force, an impulse to oblate or flat projectiles, and thereby communicating a motion of translation and one of rotation in and parallel to the planes of greatest oblateness of the projectiles.

To enable others skilled in the manufacture and use of fire-arms to make and use my invention, I will describe its make and operation in a few cases.

The barrels, chambers, and stocks of my fire-arms I propose to make of the metals and woods now used for artillery and small-arms.

The principle is to give the same, or a similar motion as that given to the scythe in mowing to flat and sharp-edged and pointed projectiles of greatest spread—*i. e.*, holding or detaining one part or point of the projectile or projectiles while the mass is swung forward and around that point or part, and when the two motions are communicated let go.

Figure 1, Plate 1, is a horizontal or lateral section of a model showing the principle as applied to projectiles like the Australian boomerang. The gun is seen in section E F G G, and Fig. 2, Plate 1, in projection E F G G, and in perspective in Figs. 3 and 4. A number of these flat and sharp pointed and edged projectiles are seen, P P P, horizontal section, Fig. 1, Plate 2, and vertical projection, or looking into the muzzle of the mortar, Fig. 2, Plate 2, in p p p p. Upon the ignition of the powder in the chamber O T, the arms are swung around on the point B, held, if necessary, by the slide or screw-head x x, which is made to project more or less over said point, as in the figure, and f is the fulerum.

It is evident that numerous applications of this principle of flat projectiles moving forward and rotating edge first can be made, in which various forms can be given the projectiles, the shape, weight, size, and solidity of the projectile depending upon the end in

view, and the nature and form of the gun and chamber also. For instance, the fulerum f can be changed, and when double knives, as P P P, are used the prongs or arms can be increased or diminished, as in Fig. 1, Plate 3, (regard being had to the charge.) Should a shower of flat and sharp projectiles be desired, a series of concentric rings cut from plates, as P P P, Fig. 3, Plate 3, can be laid, one series upon another, and all put in a cylindrical box with flat top and bottom, and the whole fired from a mortar whose interior is projected horizontally in R S F, Fig. 3, Plate 3, F G H K being a section (vertical) of the box at the muzzle.

O is the chamber, and f the fulerum, made by a projection from the gun or box into a corresponding notch of box or gun. Hollow or solid disks with sharp edges, as P, Fig. 4, Plate 3, can be fired from long barrels L R L R by setting them in sabots or culots, as S S, the four walls of the barrel being planes, A B C D being a cross-section cut by a plane perpendicular to general direction of the barrel. The rotary motion is given as the projectile leaves the mouth of the piece by a projection, f, on one side of the muzzle.

Flat and sharp semicircular rings or other armed projectiles can be fired from guns of small caliber and weight (the rings or arms being of great speed) by inserting one extremity of the ring or arm into the flat and curved chamber, as R R, Plate 2, Fig. 2, and giving the impulse to that end by the powder in C, the center of first rotation being at L or at the other extremity of the projectile, as S S. A section of the gun R R is (on the inside) a parallelogram, the cutting-plane passing through the axis at L. The form of the interior varies with that of the projectile and of the axis of rotation. Should the extremity of the arm receiving the impulse describe arcs, (with the other end as a center of rotation,) as M' L', these arcs might be projections of the walls of the gun and show part of the projectile therein.

Explanation of the trajectory or curve described by a flat circular disk moving forward and rotating.—Suppose we start the projectile with its flat sides horizontal. Flat projectiles rotating in planes parallel to their flat sides, (and having motion of translation in a uniform resisting medium, as the atmosphere, and having

the center of gravity and mass the same,) will have three forces opposed to their continuing both motions unchanged. The first is the resistance of the atmosphere due to the motion of translation alone, the rotary motion not now being considered. If the projectile is homogeneous and symmetrical with regard to the plane of fire, this first force will not deflect it from that plane. The second opposing force is the modification of the resistance of the atmosphere to motion of translation when the rotary motion is considered. If we consider the projectile with reference to its right and left halves (as divided by the vertical plane of fire or planes parallel thereto) while it is in motion, we will find that the rotary force moves with the projectile (in its motion of translation) on the one side, and is opposed to it on the other, and therefore the sum of this rotary force and atmospheric resistance due to force of translation is opposed to motion on the one side, and then difference on the other side of this vertical plane of fire, or the projectile is most retarded on the side where the motion of rotation and translation accord. The third force acting on the projectile, (its weight,) now, one side being more retarded, the side thus retarded sinks, and supposing the plane of rotation to have been a horizontal plane at the beginning, it becomes an inclined plane, the inclination or falling being on the side where the motion of rotation is forward. If any body is moving forward in a resisting medium, and an obstacle on the one side is made to oppose its motion more than on the other, (as turning the rudder of a boat or the tail of a bird to the right,) the body turns to that side in its motion forward, and describes a curve, the atmosphere acting as a fulcrum; hence the flat projectile retarded by rotation forward on the one side turns or is deflected toward that side. The inclination of its plane of rotation on the side retarded then begins, owing to its weight, and this deflects it still more toward that side, and the body then slides toward the ground in the direction of this increasing inclination; hence, to counteract this inclination or deflection of the projectile from the plane of fire, it is necessary to give it an inclination to the side

opposite to that (in which the rotary motion is forward) and from the horizontal plane.

Another cause of deflection of ordinary projectiles is the non-accordance of the center of gravity and center of mass. This can also be arranged in flat rotary projectiles to produce or counteract deflection from the vertical plane of fire.

The advantages of my projectiles are in their great spread or sweep horizontally, their great penetration in resisting media, as water, (through which loaded flat shells can be fired,) in the very small charges and light pieces of artillery, and in the light projectiles, (since being fired edge and point first wooden projectiles, by my plan, can be now discharged from fire-arms and do great execution and attain great range,) and in the ease of turning them in their course. To assure those not familiar with the subject how such have succeeded, I can state that I fired from a small brass mortar, similar to the one shown in section, Plate 3, Fig. 3, at the same time or discharge twelve flat steel half-rings or knives, each about five inches across, and with an elevation of the plane of rotation of five degrees and an inclination of seven degrees from the horizontal, and a charge of powder equal to one-half the charge of a United States musket; I obtained, with accuracy, a penetration of one inch at thirty feet, of one-half an inch at ninety feet in wood, and a range of over one hundred yards, the projectiles spreading horizontally and moving with flat sides toward the ground, and this with the first gun cast for knife-shooting, the gun or mortar weighing twenty-one pounds, and the twelve steel knives about two-thirds of a pound, the gun resting on the level ground.

What I claim in my invention is—

The use and control of flat projectiles discharged from fire-arms, or not by hand, and rotating in their flight, substantially as described.

E. O. C. ORD.
